Des. 207,864
Patented June 6, 1967

207,864

FINGER RING

Melvin H. Witcher, 1312 W. Austin,
Port Lavaca, Tex. 77979

Filed June 13, 1966, Ser. No. 2,647

Term of patent 14 years

(Cl. D45—10)

FIG. 1.

FIG. 2.

FIG. 1 is a perspective view of a finger ring, showing my new design; and

FIG. 2 is a plan view thereof in a developed flat form. The drawing is lined to represent the colors of yellow gold and white gold.

I claim:

The ornamental design for a finger ring, as shown and described.
